United States Patent Office

Des. 190,804
Patented July 4, 1961

190,804

CHAIR

Roland C. Howell, Jr., Waterport, N.Y., assignor to S. A. Cook & Co., Medina, N.Y., a corporation of New York

Filed May 3, 1960, Ser. No. 60,441

Term of patent 14 years

(Cl. D15—1)

Fig. 1.

Fig. 2.

Fig. 3.

FIG. 4.

FIG. 5.

FIG. 1 is a top plan view of a chair embodying my new design.

FIG. 2 is a side elevational view thereof, the opposite side view being substantially the same.

FIG. 3 is a front elevational view thereof.

FIG. 4 is a rear elevational view thereof.

FIG. 5 is a bottom plan view thereof.

The characteristic features of my design are shown by means of full lines in the drawing.

I claim:

The ornamental design for a chair, substantially as shown and described.
